United States Patent Office.

JOSEPH H. BERRET, OF NEW YORK, N. Y.

Letters Patent No. 74,657, dated February 18, 1868.

IMPROVEMENT IN HAND-STAMPS.

The Schedule referred to in these Letters Patent and making part of the same.

TO ALL WHOM IT MAY CONCERN:

Be it known that I, JOSEPH H. BERRET, of the city, county, and State of New York, have invented a new and improved Combined Stamp and Cancelling-Device, and that the following description, taken in connection with the accompanying drawings, hereinafter referred to, forms a full and exact specification of the same, wherein I have set forth the nature and principles of my said improvements, by which my invention may be distinguished from all others of a similar class, together with such parts as I claim, and desire to have secured to me by Letters Patent.

This invention relates to a new and improved device, by which revenue-stamps may be marked or printed, and cancelled at the same time.

The invention consists in applying a cutting-device to the ordinary hand-stamp, in such a manner that when the face of the stamp is forced down upon the revenue-stamp, and the latter printed with the name of the party or firm cancelling the stamp, the cutters applied to the hand-stamp will perforate the revenue-stamp, and effectually cancel the same. In the accompanying sheet of drawings—

Figure 1 is a side view of my invention, partly in section.

Figure 2, an inverted plan or face view of the hand-stamp and cutting-device, and

Figure 3 a vertical section.

Similar letters of reference indicate like parts.

A represents a standard or support, provided with two arms, *a a*, in which a vertical cylindrical arbor, B, is fitted, and allowed to slide freely up and down. On the lower end of this arbor B, the die or stamp C is secured, on the face of which, in raised letters, is the name of the party or firm for whom the implement is designed, provision being made for the insertion of movable-type figures for dates. This stamp C is retained elevated a suitable distance above the bed D, on which the stamp is pressed, by means of a spiral spring, E, the lower end of which bears against the lower arm *a* of the support, and the upper end against a screw or pin, *b*, fitted in the arbor B, as will be fully understood by referring to fig. 1. The arbor B is tubular, and within it there is fitted a sliding rod, F, which passes through the centre of stamp C, and has a cutter, G, on its lower end. On the upper end of the rod F there is fitted a knob, H, and around said rod, below the shank of the knob, there is fitted a spiral spring, I, which has a tendency to keep the cutter G elevated within the stamp C, so as to be above the face of the same.

From the above description, it will be seen that by striking or forcing down the knob H, the cutter G and stamp C will be forced down, and it is designed that the spring E shall be weaker than the spring I, so that the stamp C will be forced or pressed down upon the revenue-stamp first, and print the same, the cutter G then following, and piercing or cutting through the revenue-stamp, the latter being previously placed on the bed D, which may be of India rubber or other suitable material.

The construction of the device above described may be materially simplified by dispensing with the sliding rod F, and having the cutter G attached permanently to the face of the stamp C, but the former plan I deem preferable.

Having thus described my invention, I claim as new, and desire to secure by Letters Patent, as a new article of manufacture—

A stamp and cancelling-device, constructed as described, consisting of the vertical arbor F, bearing the cutters G, working through the tubular arbor B and annular stamp C, whereby the knob H, and its collar upon the arbor F, operate the arbor B and stamp C, as herein shown and described.

JOSEPH H. BERRET.
